BOTTLE REFRIGERATING AND VENDING MACHINE

William E. Port, Richmond Heights, Mo., assignor to Coca Cola Bottling Company, St. Louis, Mo., a corporation of Delaware

Application February 17, 1937, Serial No. 126,125

5 Claims. (Cl. 312—36)

This invention relates to vending machines, and with regard to certain more specific features, to automatic bottle refrigerating and vending machines.

5 Among the several objects of the invention may be noted the provision of a vending machine of the class described, which is adapted to handle bottled beverages and the like, for dispensing the same, which machine is equipped 10 with mechanism providing that the machine will dispense a bottle only upon the presentation of a coin of predetermined denomination thereto; the provision of a vending machine of the class described in which the said mechanism is unusually 15 simple in construction and operation, and contains a minimum number of operating parts that are likely to get out of order; the provision, in a machine of the class described, of means whereby the machine will receive a coin for a dispensing operation only when a bottle is available 20 to be dispensed, and is in dispensing position; the provision, in a vending machine of the class described of means whereby not more than one bottle may be dispensed for any one coin presented; and the provision of a vending machine of the class described which is relatively 25 simple and economical in construction and operation. Other objects will be in part obvious and in part pointed out hereinafter.

30 The invention accordingly comprises the elements and combinations of elements, features of construction, and arrangements of parts which will be exemplified in the structures hereinafter described, and the scope of the application of 35 which will be indicated in the following claims.

In the accompanying drawings, in which is illustrated one of various possible embodiments of the invention,

Fig. 1 is a front elevation of a vending machine embodying the present invention;

Fig. 2 is a side elevation of the machine of Fig. 1;

Fig. 3 is a vertical section taken substantially along line 3—3 of Fig. 1;

45 Fig. 4 is a fragmentary enlarged vertical section of a delivery mechanism;

Figures 5 and 6 are views similar to Fig. 4, illustrating successively advanced positions of the mechanism;

50 Fig. 7 is a top plan view of the mechanism of Fig. 4; and,

Fig. 8 is a vertical section taken substantially along line 8—8 of Fig. 4.

55 Similar reference characters indicate corre-

sponding parts throughout the several views of the drawings.

Referring now more particularly to Figures 1, 2 and 3, numeral 1 indicates the casing or enclosure of the vending machine of the present 5 invention. This casing or enclosure 1 is preferably of a hollow-wall type of construction, as indicated in Fig. 3, the hollow portions of the wall being filled with heat insulating material such as that indicated at numeral 3, at least in 10 the upper regions of the casing. The casing 1 is of a generally rectangular, box-like construction, with the exception of a sloping face 5 provided across the front upper edge thereof. The sloping face 5 receives and mounts a double window 7, 15 made of glass or some similar transparent material, so that the interior of the casing may be seen.

Internally, the casing 1 is divided into a relatively large upper compartment 9 and a smaller lower compartment 11. A partition 13, which, like the walls of the casing, is preferably of insulated construction, separates the compartments 9 and 11. It is not important that the walls of the compartment 11 be of the heat insulating construction, because all refrigerating is done in 20 the upper compartment 9.

Access to the upper compartment 9 is provided by means of a horizontally hinged door 15 in the upper region of the back of the casing. 30 The door 15 is provided with a suitable handle and locking mechanism 17 whereby a supplier of the bottles to be vended can obtain access to the interior of said compartment 9. Ordinarily, the back of the compartment 11 is left open, as 35 indicated at numeral 16. Compartment 11 is usually provided with an empty bottle-receiving tray or box 17, that is inserted through the opening 16. A chute 19 extends through the front of the case 1 and is positioned to receive empty 40 bottles and deliver them into the box 17.

In the bottom of the compartment 9, and resting upon the partition 13, there is preferably provided a grill or like device 21, which provides regular spaced openings or receptacles 23 for receiving 45 the bottles to be dispensed, indicated generally by numeral 25. Generally speaking, bottles 25 are delivered from the compartment 9 through a chute 27, which may be opened for the delivery of a bottle only upon the presentation of a coin 50 of suitable denomination to a coin control device indicated generally by numeral 29. The manner in which the coin control device 29 and the chute 27 are constructed and operate is indicated in greater detail hereinafter, and forms 55

one of the principal objects of the present invention.

In order to provide that the purchaser may move a bottle from one of the receptacles 23 into the inside top of chute 27, a manipulating device indicated generally by numeral 31 is provided. The manipulating device 31 comprises a ball 33 that is received in a universally swivelling joint 35 in the top of casing 1. Slidably extending through the center of the ball 33 is a handle or arm 37, the lower end of which carries a clamp comprising a pair of spring-pressed fingers 39. A purchaser need only stand outside of the box 1 and manipulate the outer end of the handle 37 so as to bring the clamp 39 around the neck of a bottle 25. The purchaser can observe his movements through the window 7. He then pulls the handle 37 upwardly through the ball 33, swivels the ball through whatever angle is necessary, and deposits the bottle in the top of the chute 27. It is then a simple matter for him to disengage the clamps 39 from the neck of the bottle, and release the handle 37 for a subsequent dispensing operation.

If the purchaser then places his coin in the coin control device 29, and manipulates it in a manner hereinafter to be described, the bottle he has selected will be released and slide outwardly through the chute 27 to the portion thereof outside the casing 1, where the bottle is free to be lifted by the purchaser. A convenient accessory on the outside of the casing 1 comprises a bottle cap remover 41, which includes a catch-all 43 for receiving the bottle caps removed.

In ordinary operation, after all of the compartments 23, or any desired number thereof, are filled with bottles 25, crushed ice or iced water or some similar refrigerating medium is filled into the compartment 9 until it establishes a liquid level such as that indicated at numeral 45 in Fig. 3. The bottles 25 are thus all chilled, or refrigerated, during the time that they await dispensing.

The constructions of the chute 27 and coin control device 29, and the manner of their co-operation, are indicated in Figures 4 through 8, inclusive, to which attention is now directed. The chute 27 comprises a tubular section 47, which is of sufficient internal diameter to freely pass a bottle 25. The tube 27 is mounted in the walls of the casing in a sloping manner, as indicated in Fig. 4, so that its inner end is sufficiently higher than its outer end, that the force of gravity always tends to make a bottle slide down the chute to the outer end thereof. At its upper end, the tubular portion 47 turns slightly upwardly, as indicated at numeral 49, and a portion of the tube, indicated at numeral 51, is removed, in order to provide room for certain operating mechanisms to be described. The upper end of the section 49 is normally open, so that it may receive the bottom of a bottle presented to the chute.

Closing the lower end of the tube 47, at the point that it emerges through the walls 3 of casing 1, is a closure 53 that is freely pivoted on a pin 55 mounted in ears 57 extending upwardly from the tube 47. Gravity normally holds the closure 53 shut, but said closure is free to rotate away from the end of tube 47 whenever a bottle comes down the chute. Also attached to the lower end of the tube 47 is a cradle or bottle receiving device indicated generally by numeral 59. The lower end 61 of this cradle 59 is closed, 75 in order to check the advance of a bottle being

delivered. Since the dispensed bottles are ordinarily wet from the refrigerating medium in the compartment 9, a pipe or tube 63 is preferably connected to the lower end of the basket 59 and brought back into the casing 1 at such a point that it delivers the collected drippings of ice water to an unobjectionable location (see Fig. 1).

Extending upwardly from the upper edge of the tube 47 are a pair of ears 65 which serve to mount a pin 67, the axis of which is at right angles to the axis of the tube 47. Swinging on the pin 67 is a trip member or gate 69, which comprises a flat camming portion 71 that extends through a slot 73 (see also Figures 5 and 6) into the interior of tube 47, and a stop member 75 proper indicated by numeral 75 at its opposite end. At a lower point on the tube 47, but still within casing 1, a pair of studs 77 mounted on diametrically opposite points of the outside of tube 47 serve to pivotally mount the opposite sides of a U-shaped yoke 79. Numeral 81 indicates a finger that projects downwardly from the central portion of the yoke 79, through the slot 73, and into the interior of the tube 47. Extending upwardly from the same portion of the yoke 25 are a pair of ears 85, which serve to mount a pin 87 for manipulative purposes hereinafter to be described.

Gravity normally holds the gate member 69 so that the camming portion 71 thereof extends across a substantial portion of the passage through tubes 47. Gravity likewise normally holds the finger 81 of member 79 in position across the passage through tube 47. Both the members 71 and 81 extend sufficiently far into the tube 47 that it is impossible for a bottle 25 to slide down the tube 47 without pushing both members 71 and 81 aside.

The coin controlled device 29 will readily be recognized, from Figures 4, 5 and 6, as being, basically, of the slide type. It comprises a track 89 in which slides a bar 91, the bar 91 being provided with a handle 93 at its outer end. A spring-pressed finger 95 is mounted on ears 97 raised from the track 89. The slide 93 contains a hole of suitable diameter to receive the predetermined denomination of coin. The coin is placed in the hole flat-wise, in a manner such that it forms a substantial continuation of the slide 91. If a coin is present in the slide 91 when the handle 93 is pushed inwardly, so as to make the slide 91 slide inwardly in the track 89, the finger 95 slides freely over the surface of the coin and movement of the slide member 93 is not impeded. However, if no coin is present in the hole, as soon as the hole reaches the finger 95, the finger 95 falls therein, and prevents further sliding movement of the slide 91 in the track 89.

Numeral 99 indicates an extension that is secured to the rear end of the slide 91. The extension 99 has a downwardly turned end 101, to which is hooked one end of a tension spring 103. The other end of the tension spring 103 is fastened to the wall 3 (see Fig. 7) the tension spring 103 thus serving to tend to return the slide 91 to its outwardly extended position after each manipulation of the device.

Secured to the underside of the slide 91 is a cam plate indicated generally by numeral 105. At its rearmost edge, the cam plate 105 has a notch 107, 70 which receives the portion 75 of swingable gate 69. An intermediate portion of the cam plate 105 is provided with a substantially horizontal notch 109, while the forward portion of the cam plate 105 is provided with a substantially vertical notch 75

111. The bottom edge 113 of the cam plate 105 ahead of the notch 111 is higher than the bottom edge 115 of said plate 105 ahead of the notch 111, for reasons hereinafter to be made clear.

5 A sheet metal cover 117 (see Figures 4 and 8) normally incloses all moving parts of the mechanism inside the box, leaving, however, a sufficient opening over the upper end of tube section 49 to receive a bottle, in the manner indicated in Fig. 4. 10 The cover 117 is preferably mounted on angle brackets or like members 119 secured to the inside wall of the casing.

15 The operation of the coin controlled device is such that it normally delivers, or drops the coin which has been fed to it, in a region intermediate between the two walls of the casing, such region being indicated in Fig. 4 by numeral 121. The region 121 is accordingly left hollow in the casing, and a chute 123 (see also Fig. 8) is provided between the walls leading from said region 121 to the opening 125 of a coin-receiving box 127. Locking means is provided on the handle 17, in order that the door may be opened and access to the box 127 may be had only by a duly authorized representative provided with a key.

20 The operation of the coin-controlled delivery chute mechanism as thus described is as follows:

25 Figure 4 indicates the normal, or non-operating position of all of the elements. It will be seen that the portion 75 of gate element 69 interlocks with the notch 107 in the rear end of cam plate 105 attached to coin slide 91. This is true only so long as no bottle is present in the upper end of the chute 27. If a purchaser now places a coin in the slide 91, in an attempt to manipulate the same, he will find that the coin control mechanism 29 will not slide backwardly, or receive his coin, because of this engagement of the member 75 with the notch 107. This action prevents the device from receiving a coin without at the same time delivering a bottle in exchange therefore, in the manner hereinafter to be described. In this manner, receiving of coins by the device after 40 the supply of refrigerated bottles has been exhausted, is prevented.

45 If, however, the purchaser, by manipulating the handle 37 in the manner described, has placed a bottle 25 in the upper end of the chute 27, then this bottle will, under the force of gravity, slide down the tubular portion 47 until its bottom abuts the finger 81. In so doing, it will push aside the cam portion 71 of gate element 69, and the various elements will then assume the position indicated 50 in Fig. 5.

55 By reference to Fig. 5, it will be seen that the bottle 25 has pushed aside the camming portion 71 of element 69, and in so doing has rotated said element 69 on the pin 67 to withdraw the portion 75 from engagement with the notch 107. Gravity, alone, however, will not push aside the finger 81, because the pin 87 on projecting ears 85 engages the lower edge 113 of cam plate 105. However, if the purchaser now places his coin in the slide 91, 60 and provided the coin is of a suitable denomination, the slide 91 can be pushed rearwardly in the track 89, because the portion 75 no longer engages the obstructing notch 107. As the slide 91 progresses rearwardly, it carries with it the camming 65 plate 105, and soon the pin 87 comes into juxtaposition with notch 111 and is forced to slide upwardly in said notch 111, thus rotating the yoke 79 on studs 77 and pulling the finger 81 out of the way of the bottle 25. The bottle 25 is now free to 70 travel on in the tube 47, and it does so, pushing 75

aside the cover 53 and presenting itself to the purchaser in the cradle or basket 59. Fig. 6 indicates the position of the elements at this stage of operation. It will now be seen that the purpose of the notch 109 in the cam plate 105 is to receive 5 or pass the pin 67, so that said pin does not offer an obstruction to the rearward movement of the slide 91.

By reference to Fig. 6, it will be seen that a second bottle cannot now be delivered to the open 10 inner end of the chute 27 for delivery, because the extension 99 mounted on the slide 91 forms a 15 gate or bar across the opening of receiving end 49 of the chute 27. This position of the elements makes it impossible, for example, for a purchaser 20 to surreptitiously position a second bottle in the chute for delivery merely upon the presentation of one coin. On the contrary, it is necessary that the slide 91 be released and permitted to return to its Fig. 4, or extended position, before 25 another bottle can be placed in the chute 27. And then, to secure delivery of the said second bottle, it is necessary to go through the manipulation of placing a second coin in the slide 91, and to repeat 30 all of the operations hereinbefore described. The dimensioning of the various parts of the apparatus is such that the finger, or gate 81 cannot be withdrawn from position until the said extended portion 99 of the slide 91 is in location to prevent the insertion of a second bottle into the chute.

35 It will accordingly be seen that the broad function of the various devices heretofore described is as follows: The pivoted gate member 69 is for the purpose of preventing the operation of the coin control mechanism 29 until a bottle is in 40 position for delivery. If no bottle is available in the cooling chamber 9 of the device, obviously, then, the device will not receive any money. The gate 81 prevents the delivery of a bottle in the chute until the coin of the proper denomination has been placed in the coin control mechanism 29, and said mechanism has been suitably actuated. The extending portion 99 of the slide 91 45 constitutes a second gate, which, by the very operation of releasing the first gate 81, locks the chute 27 so that a second bottle cannot be delivered until the entire sequence of operation has been repeated.

The chute 27 is thus, in effect, equipped with 50 two gates, comprising the gate 81 and the extension 99. At no time during the operation of the device are both of these gates open at the same time. Normally, the gate 81 is closed and the gate 99 is open. To deliver a bottle, the gate 55 81 opens and the gate 99 closes. And, furthermore, manipulation of any of the moving parts of the device is impossible until a bottle has been positioned to be delivered, because of the action of the device 69 in the manner heretofore described.

60 It will be obvious that upon suitable changes of size and proportion and shape of the various parts, the dispensing mechanism herein described may be adapted for the vending of articles other than bottles.

65 In view of the above, it will be seen that the several objects of the invention are achieved and other advantageous results attained.

70 As many changes could be made in carrying out the above constructions without departing from the scope of the invention, it is intended that all matter contained in the above description or shown in the accompanying drawings 75

shall be interpreted as illustrative and not in a limiting sense.

I claim:

1. In a dispensing device, a tubular chute, means supporting said chute in a sloping manner, said chute having a receiving mouth at the upper end thereof and a delivery mouth at the lower end thereof, means pivoted on said chute and having a projection extending through a slot in said chute, said projection, in its normal position, constituting an obstruction to the passage of articles through said chute, manually actuatable sliding means mounted above said chute, said sliding means having a retracted position and an extended position, means extending from said sliding means which, when said sliding means is in its extended position, extends across the receiving mouth of said chute and constitutes an obstruction preventing the insertion of articles into said chute, said sliding means also having means thereon cooperating with said pivoted means, whereby when said sliding means moves from its retracted position to its extended position, it withdraws said projection from obstructing position within said chute, said sliding means, in its retracted position, holding said projection in obstructing position across said chute.

2. In a dispensing device, a tubular chute, means supporting said chute in a sloping manner, said chute having a receiving mouth at the upper end thereof and a delivery mouth at the lower end thereof, means pivoted on said chute and having a projection extending through a slot in said chute, said projection, in its normal position, constituting an obstruction to the passage of articles through said chute, manually actuatable sliding means mounted above said chute, said sliding means having a retracted position and an extended position, means extending from said sliding means which, when said sliding means is in its extended position, extends across the receiving mouth of said chute and constitutes an obstruction preventing the insertion of articles into said chute, said sliding means also having means thereon cooperating with said pivoted means, whereby when said sliding means moves from its retracted position to its extended position, it withdraws said projection from obstructing position within said chute, the said last-named means comprising a vertical camming plate extending from the said sliding means and adapted to engage a projection extending upwardly from said pivoted means, said sliding means, in its retracted position, holding said first-named projection in obstructing position across said chute.

3. In a dispensing device, a tubular chute, means supporting said chute in a sloping manner, said chute having a receiving mouth at the upper end thereof and a delivery mouth at the lower end thereof, means pivoted on said chute and having a projection extending through a slot in said chute, said projection, in its normal position, constituting an obstruction to the passage of articles through said chute, manually actuatable sliding means mounted above said chute, said sliding means having a retracted position and an extended position, a portion of said sliding means, when in its extended position, extending across the receiving mouth of said chute and constitutes an obstruction preventing the insertion of articles into said chute, said sliding means also having means thereon cooperating with said pivoted means, whereby when said slid-

ing means moves from its retracted position to its extended position, it withdraws said projection from obstructing position within said chute, and a locking device pivotally mounted on said chute and having one portion adapted to engage said sliding means and another portion adapted to project into said chute, said locking device being adapted to be rotated to a position such that it does not obstruct the movement of said slide, when an article is in said chute in position to be delivered, said sliding means, in its retracted position, holding said projection in obstructing position across said chute.

4. In a dispensing device, a tubular chute, means supporting said chute in a sloping manner, said chute having a receiving mouth at the upper end thereof and a delivery mouth at the lower end thereof, means pivoted on said chute and having a projection extending through a slot in said chute, said projection, in its normal position, constituting an obstruction to the passage of articles through said chute, manually actuatable sliding means mounted above said chute, said sliding means having a retracted position and an extended position, a portion of said sliding means, when in its extended position extending across the receiving mouth of said chute and constituting an obstruction preventing the insertion of articles into said chute, said sliding means also having means thereon cooperating with said pivoted means, whereby when said sliding means moves from its retracted position to its extended position, it withdraws said projection from obstructing position within said chute, and a locking device pivotally mounted on said chute and having one portion adapted to engage said sliding means and another portion adapted to project into said chute, said locking device being adapted to be rotated to a position such that it does not obstruct the movement of said slide, when an article is in said chute in position to be delivered, but, under the force of gravity, to assume a position obstructing movement of said sliding means when no article is in the chute in position for delivery, and sliding means, in its retracted position, holding said projection in obstructing position across said chute.

5. In a dispensing device, a tubular chute, means supporting said chute in a sloping manner, said chute having a receiving mouth at the upper end thereof and a delivery mouth at the lower end thereof, means pivoted on said chute and having a projection extending through a slot in said chute, said projection, in its normal position, constituting an obstruction to the passage of articles through said chute, manually actuatable sliding means mounted above said chute, said sliding means having a normal retracted position and an extended position, means extending from said sliding means which, when said sliding means is in its extended position, extends across the receiving mouth of said chute and constitutes an obstruction preventing the insertion of articles into said chute, said sliding means also having means thereon cooperating with said pivoted means, whereby when said sliding means moves from its retracted position to its extended position, it withdraws said projection from obstructing position within said chute, said chute also being provided with a non-obstructing closure at its lower, delivery end, said sliding means, in its retracted position, holding said projection in obstructing position across said chute.

WILLIAM E. PORT.
